TRIP-FREE SWITCH MECHANISM COMPRISING A LATCH CARRIED BY A THRUST-TRANSMITTING CAM

Roy F. Kidd, Wauwatosa, Wis., assignor to Allis-Chalmers Manufacturing Company, Milwaukee, Wis., a corporation of Delaware

Application March 20, 1947, Serial No. 736,063

5 Claims. (Cl. 200—109)

1

This invention relates in general to improvements in switch-operating mechanisms, and more particularly to a trip-free mechanism adapted for manual actuation of a switch of the contactor type.

It is an object of the present invention to provide an improved trip-free switch-operating mechanism involving a minimum number of parts.

Another object of the present invention is to provide an improved trip-free switch mechanism in which all parts are always exposed for inspection.

Another object of the present invention is to provide an improved trip-free switch mechanism in which all parts are always accessible.

Objects and advantages other than those above set forth will be apparent from a consideration of the following description when read in connection with the appended drawing, in which:

Fig. 1 is a view in front elevation of one embodiment of the present invention adapted for manual actuation of a switch of the contactor type, showing the elements thereof in the position reached thereby in response to electrical tripping operation;

Fig. 2 is a view in side elevation of the embodiment illustrated in Fig. 1, some of the elements of the actuating mechanism and of their support being assumed removed to clarify the drawing;

Fig. 3 is a view similar to Fig. 2 showing the elements of the mechanism in position for trip-free closure of the switch;

Fig. 4 is a view similar to Fig. 2 showing the elements of the mechanism in the position reached thereby when the switch reaches the closed position; and

Fig. 5 is a view similar to Fig. 2 showing the elements of the mechanism in the position reached thereby when the switch has been tripped manually.

Referring more particularly to the drawing by characters of reference, numeral 6 generally designates a switch of the contactor type mounted on an insulating panel 7. Switch 6 may be of any known type and may comprise a fixed contact 8 resiliently mounted on a bracket 9 supported on panel 7. A cooperating movable contact 10 is rigidly mounted on an arm 11 fastened to a shaft 12. Contact 10 is biased toward the open position shown in Fig. 1 by suitable means, such as a spring 14 urging arm 11 against a suitable stop (not shown). Shaft 12 is supported in a suitable number of bearings 15 mounted on panel 7.

The actuating means for switch 6 comprise an

2

operating handle 16 mounted on a shaft 17. The outer end of the shaft is supported in a bearing 18 which may be mounted on any suitable support such as a cubicle wall 19. The inner end of shaft 17 is preferably pivoted on a pin 21 inserted in a bore provided in the adjacent end of shaft 12.

Shaft 17 carries a stop block 22 and may be rotated in both directions from the position shown to an extent limited by engagement of the stop block with the front surface of panel 7. Shaft 17 is biased toward the position shown by means of a torsion spring 23. The spring is provided with extensions which straddle a lug 24 mounted on bearing 18 and may alternately be engaged by a pin 25 mounted on shaft 17. Elements 18, 19, 23, 24 and 25 are shown only on Fig. 1.

The operative connection between shafts 12 and 17 is effected by a linkage comprising a driving crank 26 mounted on shaft 17 and a driven crank 27 mounted on shaft 12. The two cranks may be connected through a thrust-transmitting linkage comprising a pin 28 fastened on crank 26 and a cam 29 consisting of a pair of identical pieces of sheet metal disposed on both sides of crank 27.

For closing switch 6, thrust may be transmitted between cranks 26 and 27 through pin 28 and a cam surface 31. Cam 29 is also provided with a cam surface 30 to be engaged by pin 28 to cause manual tripping of switch 6. Cam 29 is pivotally connected with crank 27 through a pin 33 and is urged away from its thrust-transmitting position into the position shown in Fig. 2 by means of a spring 32.

Cam 29 may be moved into thrust-transmitting position with respect to crank 26 by tripping means comprising suitable current responsive means such as a solenoid 35. The solenoid is provided with an armature 36 having a limited stroke, which carries a pin 37 retained in an arcuate slot 38 of cam 29.

Cam 29 carries a latch 39 pivoted thereon by means of a pin 40 and resiliently urged against a stop 41 by a spring 42. Latch 39 extends through a window provided in panel 7 and is adapted to catch on a fixed hook 43 mounted on panel 7 to hold switch 6 in closed position.

Figs. 1 and 2 show the elements of the mechanism after tripping has been effected by deenergizing solenoid 35. Armature 36 is in the deactuated position shown, and cam 29 is moved out of thrust-transmitting position into a position determined by the stroke of solenoid armature 36. If handle 16 is then moved in either direction of rotation, the movement of the handle is stopped by engagement of stop block 22 with the surface

of panel 7 before pin 28 can engage any surface of cam 29.

To close switch 6, solenoid 35 must first be energized. The solenoid attracts its armature 36, which lifts pin 37. The pin causes cam 29 to pivot about pin 33 into the position shown in Fig. 3, which is the thrust-transmitting position with respect to crank 26. The center of the arcuate edges of slot 38 is thereby moved to a position on the common axis of shafts 12 and 17.

When handle 16 is moved clockwise against the action of spring 23, pin 28 first travels freely and thereafter engages cam surface 31. Further movement of handle 16 causes crank 26 to drive crank 27 into actuated position through pin 28 and cam 29 to bring switch 6 into the closed position shown in Fig. 4. During such movement, cam 29 is continuously supported on pin 37 through the upper edge of slot 38 and slides on the pin. Cam 29 and cranks 26, 27, 20 then move as if they were rigidly united. Toward the end of such movement, latch 39 rides over the edge of hook 43 while pivoting about pin 40 to compress spring 42. When cam 39 reaches the position shown in Fig. 4, spring 42 urges latch 39 against stop 41 in a position in which the latch catches on hook 43. When handle 16 is released and is returned by spring 23 into the position shown in Fig. 2, the elements of the mechanism not rigidly connected therewith remain in the position shown in Fig. 4.

When switch 6 is closed, the switch may be tripped by deenergizing solenoid 35. Armature 36 drops into the position shown in Fig. 2 under the action of gravity and of spring 32 acting thereon through cam 29. The cam pivots about pin 33, thereby raising latch 39 out of engagement with hook 43. Springs 14 and 32 then return the elements of the mechanism into the position shown in Fig. 2.

Tripping may also be effected manually by moving handle 16 counterclockwise into the position shown in Fig. 5. During such movement, pin 28 first travels freely and thereafter engages surface 30 of cam 29. Further movement of handle 16 causes pivotal movement of cam 29 about pin 33. The cam forces armature 36 downward against the action of solenoid 35 and raises latch 39 out of engagement with hook 43. Spring 14 then moves switch 6 into the open position. As a result thereof, crank 27 moves cam 29 into the position shown in Fig. 5, in which position slot 28 is raised sufficiently to enable armature 36 to return to the attracted position. When handle 16 is released and shaft 17 is returned by spring 23 into the position shown in Fig. 2, the elements of the mechanism not rigidly connected therewith remain in the position shown in Fig. 5.

It will be apparent that if solenoid 35 is deenergized at any time during closing operation of switch 6, armature 36 immediately drops and spring 32 causes cam 29 to pivot about pin 33 from its thrust-transmitting position into a position disengaging surface 31 from pin 28. The elements of the mechanism other than handle 16 and the elements rigidly connected therewith then immediately return to the position illustrated in Fig. 2 to open switch 6. The switch is therefore trip-free in all its positions.

Although but one embodiment of the present invention has been illustrated and described, it will be apparent to one skilled in the art that various changes and modifications may be made therein without departing from the spirit of the

invention or from the scope of the appended claims.

It is claimed and desired to secure by Letters Patent:

1. A switch operating mechanism comprising a driving crank, a driven crank, a cam having a pivotal connection with said driven crank, current responsive means connected with said cam for moving said cam about said pivotal connection into thrust-transmitting position with respect to said driving crank, a latch mounted on said cam, and a fixed hook engaged by said latch in response to movement of said cam into said thrust-transmitting position and movement of said driving crank bringing said driven crank into actuated position.

2. A switch operating mechanism comprising a driving crank, a driven crank, a cam having a pivotal connection with said driven crank and being actuatable into a thrust-transmitting position with respect to said driving crank, a latch mounted on said cam, a fixed hook engaged by said latch in response to movement of said cam into said thrust-transmitting position and movement of said driving crank bringing said driven crank into actuated position, and current responsive means for causing movement of said cam about said pivotal connection out of said thrust-transmitting position to disengage said latch from said hook.

3. A switch operating mechanism comprising a driving crank, a driven crank, a cam having a pivotal connection with said driven crank, current responsive means connected with said cam for moving said cam about said pivotal connection into thrust-transmitting position with respect to said driving crank, a latch mounted on said cam, and a fixed hook engaged by said latch in response to movement of said cam into said thrust-transmitting position and movement of said driving crank bringing said driven crank into actuated position, said cam being provided with a cam surface engaged by said driving crank upon reversal of said movement of said driving crank into tripping position to cause movement of said cam about said pivotal connection to disengage said latch from said hook against the action of said current responsive means.

4. A switch operating mechanism comprising actuating means, a linkage operatively connected to said actuating means, a crank operatively connected to said linkage, tripping means for holding said linkage in a position for transmitting thrust from said actuating means to said crank through said linkage, a latch mounted on said linkage, and a fixed hook engaged by said latch in response to movement of said crank into actuated position.

5. A switch operating mechanism comprising a driving crank, a driven crank mounted on a shaft, a cam mounted on said driven crank and having a pivotal connection therewith at a point remote from said shaft, and current responsive means connected with said cam for moving said cam about said pivotal connection into a position for transmitting thrust from said driving crank to said driven crank through said cam.
